PROJECTION APPARATUS FOR MULTIPLE RECORD TALKING MACHINES

Al Semels, New York, N. Y.

Application November 22, 1940, Serial No. 366,627

7 Claims. (Cl. 88—28)

This invention concerns a multiple character-record exhibiting apparatus which is adapted to be in co-operation with a multiple sound-record reproducing apparatus, whereby simultaneous sound and exhibition performance will be automatically related, and more particularly, this invention relates to what may be a multiple moving-slide stereopticon with a slide selector means, adapted to be combined with a multiple record talking machine having a record selector means, whereby selection of the record to be played is made by a simple manual manipulation, whereupon simultaneously, the talking machine record chosen and its related stereopticon slide assume operating position, and the performance of said record and slide progresses in substantial unison as to subject matter.

The principal object of this invention is to provide a novel and improved means for accomplishing automatically, related operation between a multiple record talking machine having a record selector mechanism, and a multiple moveable slide projection apparatus of the stereopticon type.

A further object hereof is to provide mechanism of the type set forth, of novel and improved construction whereby the impact of components of the talking and projection machines temporarily in contact, is materially lessened, and yet the operation of which is definite and timely in accomplishment though delayed in action in order to absorb the shock of impact.

Another object of this invention is to provide mechanism of the character set forth, of novel and improved construction, whereby upon completion of a performance, the stereopticon slides are automatically returned to proper initial rest position.

A further object hereof is to provide novel and improved apparatus of the character mentioned, which is adaptable for combination with existing multi-record talking machines or to be built-in in a combined embodiment within a single cabinet designed to house the combined apparatus.

Another object hereof is to provide apparatus of the type described which is simple to adapt to existing talking machines, easy to understand as to construction and operation, positive in operation and efficient in carrying out the purposes for which it is designed.

Other objects and advantages will become manifest as this disclosure proceeds.

In the accompanying drawings forming part of this disclosure, similar characters of reference indicate corresponding parts in all the views.

Fig. 1 is a diagrammatic side elevation of a combined talking and projection machine embodying the teachings of this invention.

Fig. 2 is substantially a plan view of Fig. 1.

Fig. 3 is a side elevation showing the mechanism employed in an embodiment of this invention, for moving the lantern slide holder with respect to the projector.

Fig. 4 is a bottom view of Fig. 3.

Fig. 5 is an enlarged view of a portion shown in Fig. 2, namely, of the lantern slide selector apparatus.

Fig. 6 is a side elevation of the apparatus shown in Fig. 5.

Fig. 7 is a perspective view of a component of the apparatus illustrated in Fig. 5.

Fig. 8 is a perspective view of the lantern slide holder, which is a drum frame adapted to receive the several slides.

Fig. 9 shows a governor construction included in the embodiment hereinafter described.

In the drawings, the numeral 25 designates generally a multiple record talking machine which may be of the coin operated type having a coin deposit 26, and record selector buttons 27. There is one such button for controlling the selection of its related record. The several records 28, 29, 30 and 31, are each loosely carried in separate ferrule frames 32, which at rest position are housed at one side of the cabinet 33, one above the other in parallel relation. The record selector mechanism, omitted in the drawings, is actuated upon movement of one of said buttons 27, to shift the proper record frame 32, to a position directly over the turntable 34, which is automatically raised by an arm 35 to receive the shifted record thereon from off the frame, and then played by means of the sounding arm 36; the said frame 32, remaining in its shifted position concentrically beneath the raised operating position of the turntable 34. Upon completing playing of the record, it is again delivered into its waiting frame by lowering the turntable 34 to initial rest position, whereupon said frame

carrying the record just played, is swung back to its initial rest position among the remaining records. A lug 37, extending radially from each of the frames 32, coming into contact with the fixed stop member 38, determines the rest position of the several records. Such machines are known.

The apparatus now to be described is my contribution, which might be assembled as a unit to serve as an attachment for existing multiple record talking machines of the type mentioned.

or else be made part of newly built combinations within an enlarged cabinet as indicated in Fig. 1.

A prismatic frame structure or drum frame 39, adapted to have a series of lantern slides 40, 41, 42 and 43, removably mounted therein, preferably vertically within the channels 44 therefor provided, is axially fixed on and is slidably mounted along a vertical shaft 45. In the embodiment illustrated, I have provided the square holes 46, and therefore shaft 45 is of square cross-section.

A spiral cam 47, on shaft 48, co-operating with a lever 49 supporting said drum frame 39, and pivoted at 50, may be used to either raise or lower said lantern slide drum frame 39, as may be required. A magic lantern or other stereopticon device 51, in fixed position within the drum 39, is adapted to send its rays through the particular lantern slide directly in front thereof onto a tilted mirror or other suitable reflecting surfaced member 52, to be reflected therefrom to a reversely tilted reflecting surfaced member 53, and finally projected on the screen 54 to be viewable from in front of the entire machine.

It is preferred that the cam shaft 48, shall be driven from an electric motor 55, through a system of reduction gearing including a governor controlled clutch. For this purpose, in the embodiment shown, I provide the drive illustrated particularly in Fig. 3, where 56, is a shaft carrying a small gear 57 and a large friction wheel 58; the former being in permanent engagement with a comparatively large gear 59 on the cam shaft 48, and the latter to be engaged as desired by a comparatively small friction wheel 60, which is on stud 61 at the end of a lever 62, swingable intermediate its ends on shaft 63. Shaft 61 also carries a gear 64 which is in permanent engagement with a comparatively smaller gear 65 on the lever pivot shaft 63. This shaft 63 also carries a pulley 66, which is connected by a belt 67 to a pulley on the motor shaft 68. Said motor shaft also carries a governor indicated generally by the numeral 69, for controlling the movement of the lever 62. The friction wheels 58 and 60, are normally disengaged when the apparatus is not working, which disengagement is effected by means of the spring 70. The purpose of the governor 69, is to control engagement and disengagement of the friction wheels 58 and 60, by shifting the lever 62. Said governor may be of any type, although I have used the kind which consists of a loose outer casing 71, which houses a radially socketed wheel 72 secured on motor shaft; there being in said bores, loosely slidable friction elements 73, of weight sufficient to be thrown into frictional contact with said outer casing 71, when the motor speed develops and continues sufficiently for such purpose, and of course, when the motor speed is slowed down to a certain extent, said elements 73 will have no outwardly radial urge, and hence the casing 71 will be absolutely loose, whereupon pin 74 extending from the casing 71, will cease its downward push on the hooked end 75.

The shaft 45, extends upwardly within a casting 76, wherein said shaft carries a series of cams 77, extending radially therefrom one above another and in respectively definite angular relation with one another. Within said casing, are a series of slidably mounted plates 78, each coplanar with one of the cams 77, and normally out of contact, but capable of being slid toward said shaft 45, whereby any slide so moved will receive its related cam within an identical cam-guiding cut-out 79, which will cause the shaft

45 to turn a definite angular movement to bring the related slide of the type 40 in operating position before the projection lantern 51. The respective cam shifting plates 78, are each maintained away from the cams 77, by the springs 80 from a fixed post 81, and the springs 82, from the levers 83 respectively. These levers 83 are each pivotally mounted on an upright shaft 84, intermediate their ends. One end of which of each of them set within slots 85 in an elongated extension of the plates 78. Each of the levers 83 have respectively related arms 86, which are pivotally mounted on said shaft 84, and are each provided with a hook extension 87, and a stop element 88 which is adapted to contact the lever 83 to limit its movement or to carry it about its fulcrum as need may be. On the side of the stop elements 87, each set of lever and arm, is provided respectively with a coil spring 89, connected at one end in each instance to the end of the lever 83 and intermediate the end of the related arm 86. Each plate and cam set has its lever and arm set. However, 90 is an engagement member for all of the hooks 87, and 91 indicates the hook release member; both said members being mounted pivotally on fixed shaft 92. It is to be noted that lug 37 of each of the record frames 32, contacts and shifts both the arm 86 and the hook release 91, in the travel thereof to and from the turntable 34, and the relative position and dimensions are such to effect full accomplishment of the required functions of the various cam shifting members.

As set forth, each record of the type 28, has its related lug 37, arm 86, lever 83, cam shifter plate 78, cam 77 and lantern slide of the type 40. The shaft 92 carries thereabout a coil spring 93, secured at one end to the hook engagement member 90 and its other end to said shaft, and in like manner secured is a spring 94 to the hook release member 91 and said shaft. Said springs are normally untensed, but become tensed respectively upon movement of the said members they control, in order to return them to normal rest position. The slides of the type 40, may have thereon the words of the song of its related record of the type 28, with or without illustration, or may present in whole only pictorial representations or may have subject matter of other character in a manner related to its sound record 28. The rate of axial movement of the cam shaft 48, should be such that the drum or frame 39 shall be raised once its full range during the interval it takes to play the related record 28, so that sound reproduction and moving picture projection shall be substantially in synchronism or suitable unison. It is also evident that the afore-described projection apparatus and lantern slide selector means may be assembled as a unit for attachment to existing multiple record talking machines of the type as 25, with slight modifications where necessary to conform to mechanical structure or expediency as may be dictated by the experience of persons versed in this and related arts. Of course, the whole combination can be made as a new product of manufacture within a single suitable cabinet, instead of altering the existing cabinets of machines 25 to incorporate the projection apparatus as an adjunct thereto.

A switch 95 to control the circuit of the motor 55, is fixed within the cabinet 33, and is arranged so that a component of machine 25, which moves away from a rest position at commencement of operation of said machine 25, and

returns to such initial rest position at the conclusion of the playing of any of the records as 28, shall operate such switch to close said circuit at commencement of play, and open the circuit at the conclusion of play. In the embodiment shown as an example of this invention, the turntable raising arm 35 has been chosen for such office, meaning that upon the raising of such arm 35, it shifts the operating member of switch 95 to close the same, and upon lowering of said arm 35, it will again shift said operating member to restore the switch to open condition. The numeral 96 is a coil spring about the cam shaft 48, and is attached at one end to the frame of the structure and at its other end it is secured to said cam shaft, so that it is wound up during the operation of the combined apparatus, and therefore adapted to restore the cam 47 to initial rest position upon disengagement of the friction wheels 58 and 60. Provision is however made that such return movement of the cam shaft 48 shall be materially retarded by means of a fan governor 97 on shaft 56, to create air resistance.

When not in operation, meaning at rest position, all the frames 32 are above each other away from turntable position. The turntable 34 and the lantern slide drum frame 39 are in lowered position. Switch 95 is open, the friction wheels 58 and 60 are disengaged and the components of the lantern slide-selector mechanism are in relative position as shown in Fig. 5.

In operation, upon depositing of coin and proper shifting of member 26 and the button 27 designating the desired record as 28, mechanism of the talking machine 25 becomes actuated whereby frame 32 carrying the chosen record, will be moved to a position directly above the turntable 34 which now is made to rise and lift said record 28 thereon to playing position, whereupon the movement of arm 35 will close the switch 95 whereby motor 55 will rotate and the lamp of the lantern 51 put on. This invention is not concerned with the operating mechanism of machine 25, and therefore same is not shown, for machines of this type are well known.

During the aforesaid movement of the frame 32 to turntable position, its lug 37, coming into contact with the end of its related arm 86, will shift said arm a sufficient distance so that the related lever 83 will slide its related plate 78 to receive its related cam 77 within cut-out 79, thereby causing a measured turning of shaft 45 to the position where the lantern slide as 40, related to the sound record 28 to be performed, will assume proper position with respect to the lantern 51 for projection onto the screen 54.

It is to be noted that the impact of the lug 37 against the lever arm 86, is taken up by the spring 89, and it is this spring, and not the movement of said lug 37, which moves the lever 83 the required travel determined by the stop elements 88. It is evident that the hook 87 has become engaged by the member 90. Of course said lug 37 shifts said arm 86 a little beyond the required shifted position to be assumed by said arm, for it is required that said lug again intercept said arm 86 upon the return movement of the frame 32 after the performance of the record is completed. Spring 89 will bring the arm 86 back a little to the engagement member 90. Said lug 37 in its movement, will shift the hook release member 91 away from the engagement member 90, but being that this movement is against action of spring 94, said member 91 will be restored to its position against

the engagement member 90, as soon as the lug has disengaged it in travelling to turntable position. Upon movement of the plate 78 to cam engagement position, spring 80 has become stressed.

While the above is taking place, the speed of motor 55 has reached a sufficient rate to actuate the governor 69, whereby its outer casing 71 will be urged so that pin 74 will shift and maintain the hooked end 75 of lever 62 downward against action of spring 70, whereupon the friction wheels 58 and 60 will assume engagement, and the cam shaft 48 will rotate slowly, causing the lantern slide drum frame 39 to rise, and spring 96 will become tensed.

The sounding arm now contacts the record 28, whereby same is played simultaneously with projection of the slide 40 progressively line by line upon the screen in substantial synchronism with the talking machine performance.

Upon completion of the playing of the record, the turntable 34 is automatically lowered, and in its movement deposits the record 28 just played into its frame 32, and continues to move downward to initial rest position. During such downward movement, arm 35 will again intercept the moving element of the switch 95, causing the switch to open the circuit and thus stop rotation of motor 55, and extinguish the light source of the projection lantern 51. The frame 32 is at this time shifted back automatically by the talking machine operating mechanism, to its initial rest position among the other records, during which travel of said frame, its lug 37 will first contact and shift the release member 91 causing the engagement member 90 to move and release the hook 87 of arm 86 therefrom, whereby said arm is free to return to initial rest position, effected by said lug travel. Return of said arm 86 is assured by action of the spring 80, which restores the slide 78 to initial rest position, causing lever 83 to return to its initial rest position, and to stress the spring 89 which in turn brings said arm 86 back to its initial rest position. And although lug 37, in the return movement of the frame 32 must shift said arm beyond initial rest position in order to clear, yet in doing so, spring 82 is stressed to cause the return of all the lantern slide selector components to normal rest position. The whole apparatus is now in condition for another performance, for which any record may be chosen, because spring 70 has caused the disengagement of the friction wheels 60 and 58, and tensed spring 96 has caused the return of the cam 47 to initial rest position, at a retarded rate due to action of the fan governor 97.

This invention is capable of numerous forms and various applications without departing from the essential features herein disclosed. It is therefore intended and desired that the embodiment described herein shall be deemed illustrative and not restrictive and that the patent shall cover all patentable novelty herein disclosed; reference being had to the following claims rather than to the specific description herein to indicate the scope of this invention.

I claim:

1. In an apparatus of the character described for cooperation with a multiple record talking machine of the type having a series of record carrying frames, each having a lug extending therefrom, a turntable, means to select and move any of the frames over the turntable and upon completion of the playing of the record so moved, restore the frame carrying such record to its in-

itial rest position, and a component which moves from rest position to operating position at the commencement of operation and automatically returns to initial rest position upon completion of the playing of the record selected for performance, the combination of a frame, a shaft journalled to the frame, a drum frame axially fixed and slidably mounted on said shaft, a series of lantern slides mounted on the periphery of the drum frame, a magic lantern apparatus including a light source positioned on the frame near the drum frame, a projection screen; said magic lantern apparatus being adapted to project onto the screen, characters on the lantern slide directly in front of the lantern apparatus, means to move the drum frame a predetermined distance along the shaft, once during and consuming substantially the entire interval in which a record is completely played by the talking machine, means to automatically return the drum frame to initial rest position along the shaft upon completion of the playing of a record, a series of members adapted to co-operate with said shaft and rotate same predetermined parts of a revolution when respectively shifted, whereby the lantern slides are respectively presented before the lantern apparatus in projection operating position; each of said members being provided with a hook element extending therefrom respectively, means to engage the hooks of said members when said members are in shifted position to co-operate with said shaft, means to shift the hook engagement means out of engagement of said hook elements; said members which are adapted to rotate the shaft lying respectively in the respective paths of travel of the lugs extending from the record carrying frames, and the hook disengagement member also lying in the paths of all of said lugs; said shaft co-operating members being adapted to be operated by said lugs respectively during the travel of said lugs, and the hook detaching means being adapted to be actuated by said lugs only upon return movement of a record carrying frame to initial rest position, to shift the hook engagement means; the lantern slides being so arranged about the drum frame that the slide being projected upon the screen is related in subject matter to the record being played by the talking machine, an electric motor adapted to drive the means for moving the drum frame along the shaft during the playing of a record, and an electric switch fixed on the frame; said switch including an operating arm adapted to co-operate with said talking machine component, whereby upon movement of said component at the commencement of operation of the talking machine from initial rest position, said switch is operated to assume closed condition, and to assume open condition upon return movement of said talking machine component to initial rest position upon completion of the playing of a record by the talking machine; said switch controlling the circuits of either or both said motor and the light source of the lantern apparatus.

2. In an apparatus of the character described for cooperation with a multiple record talking machine of the type having a series of record carrying frames, each having a lug extending therefrom, a turntable, means to select and move any of the frames over the turntable and upon completion of the playing of the record so moved, restore the frame carrying such record to its initial rest position, and a component which moves from rest position to operating position at the commencement of operation and auto-

matically returns to initial rest position upon completion of the playing of the record selected for performance, the combination of a frame, a shaft journalled to the frame, a drum frame axially fixed and slidably mounted on said shaft, a series of lantern slides mounted on the periphery of the drum frame, a magic lantern apparatus including a light source positioned on the frame near the drum frame, a projection screen; said magic lantern apparatus being adapted to project onto the screen, characters on the lantern slide directly in front of the lantern apparatus, means to move the drum frame a predetermined distance along the shaft, once during and consuming substantially the entire interval in which a record is completely played by the talking machine, means to automatically return the drum frame to initial rest position along the shaft upon completion of the playing of a record, a series of cams mounted on the shaft in definite angular relation, a series of plates individually slidably mounted on the frame, and respectively co-operative with said cams when moved toward the shaft; each of said cams have a cut-out adapted to receive the related cam therein, whereby the shaft is rotated a predetermined part of a revolution so that the lantern slide related to the record being played, is presented before the lantern apparatus in operating position, a series of members movably mounted on the frame, one for each of said plates, adapted upon movement to shift the respective plates to receive the cams in the respective cut-outs singly; each of said members being provided with a hook element extending therefrom respectively, means to engage the hooks of said members when said members are in shifted position towards the shaft, means to shift the hook engagement means out of engagement of said hook elements; said members lying respectively in the respective paths of travel of the lugs extending from the record carrying frames, and the hook disengagement means also lying in the paths of all of said lugs; said plate shifting members being adapted to be operated by said lugs respectively during the travel of said lugs, and the hook detaching means being adapted to be actuated by said lugs only upon return movement of a record carrying frame to initial rest position, to shift the hook engagement means, spring means associated with each of said plates adapted to return said plates respectively to initial rest position out of contact with the cams, upon release of the hooks from the hook engagement means; the lantern slide being so arranged about the drum frame that the slide being projected upon the screen is related in subject matter to the record being played by the talking machine, an electric motor adapted to drive the means for moving the drum frame along the shaft during the playing of a record and an electric switch fixed on the frame; said switch including an operating arm adapted to co-operate with said talking machine component, whereby upon movement of said component at the commencement of operation of the talking machine from initial rest position, said switch is operated to assume closed condition, and to assume open condition upon return of said talking machine component to initial rest position upon completion of the playing of a record by the talking machine; said switch controlling the circuits of either or both said motor and the light source of the lantern apparatus.

3. In an apparatus of the character described for cooperation with a multiple record talking machine of the type having a series of record

carrying frames, each having a lug extending therefrom, a turntable, means to select and move any of the frames over the turntable and upon completion of the playing of the record so moved, restore the frame carrying such record to its initial rest position, and a component which moves from rest position to operating position at the commencement of operation and automatically returns to initial rest position upon completion of the playing of the record selected for performances, the combination of a frame, a shaft journalled to the frame, a drum frame axially fixed and slidably mounted on said shaft, a series of lantern slides mounted on the periphery of the drum frame, a magic lantern apparatus including a light source positioned on the frame near the drum frame, a projection screen; said magic lantern apparatus being adapted to project onto the screen, characters on the lantern slide directly in front of the lantern apparatus, means to move the drum frame a predetermined distance along the shaft, one during and consuming substantially the entire interval in which a record is completely played by the talking machine, means to automatically return the drum frame to initial rest position along the shaft upon completion of the playing of a record, a series of cams mounted on the shaft in definite angular relation, a series of plates individually slidably mounted on the frame, and respectively co-operative with said cams when moved towards the shaft; each of said plates being provided with a cut-out adapted to receive the related cam therein, whereby the shaft is rotated a predetermined part of a revolution so that the lantern slide related to the record being played, is presented before the lantern apparatus in operating position, a series of levers pivotally mounted on the frame intermediate their ends, adapted upon movement to shift the respective plates to receive the respective cams within the cut-outs singly; a series of arms pivotally mounted on the frame, each having a hook element extending therefrom respectively, also a spacer element extending therefrom respectively adapted to contact the respective levers and maintain the related arms and levers in definite spaced angularity, springs respectively connected at one end to arms and at the other ends to the related levers, adapted to restore and maintain the related arms and levers in their definite spaced angular relation upon movement of any of the arms, whereby the movement of the respective plates is tardy with respect to the movement of the related arms, means to engage the hooks, when the arms are shifted from rest position, means to shift the hook engagement means out of engagement of said hook elements; said arms lying respectively in the respective paths of travel of the lugs extending from the record carrying frames, and the hook disengagement means also lying on the paths of all of said lugs; said arms being adapted to be operated by said lugs during the travel of said lugs, and the hook detaching means being adapted to be actuated by said lugs upon return movement of a record carrying frame to initial rest position, spring means associated with each of said plates adapted to return said plates respectively to initial rest position out of contact with the cams, upon release of the hooks from the hook engagement means; the lantern slides being so arranged about the drum frame that the slide being projected upon the screen is related in subject matter to the record being played by the talking machine,

an electric motor adapted to drive the means for moving the drum frame along the shaft during the playing of a record and an electric switch fixed on the frame; said switch including an operating arm adapted to co-operate with the talking machine component, whereby upon movement of said component at the commencement of operation of the talking machine from initial rest position, said switch is operated to assume closed condition, and to assume open condition upon return of said talking machine component to initial rest position upon completion of the playing of a record by the talking machine; said switch controlling the circuits of either or both said motor and the light source of the lantern apparatus.

4. An apparatus as defined in claim 2, including spring connections, one between each of the plates and their related shifting members, adapted to tardily cause the shifting of the plates upon movement of any of said members by the respective lugs.

5. In an apparatus of the character described for cooperation with a multiple record talking machine of the type having a series of record carrying frames, each having a lug extending therefrom, a turntable, means to select and move any of the frames over the turntable and upon completion of the playing of the record so moved, restore the frame carrying such record so moved, to its initial position, and a component which moves from rest position to operating position at the commencement of operation and automatically returns to initial rest position upon the completion of the playing of the record selected for performance, the combination of a frame, a shaft journalled to the frame, a drum frame axially fixed and slidably mounted on the shaft, a series of lantern slides mounted on the periphery of the drum frame, a magic lantern apparatus including a light source positioned on the frame near the drum frame, a projection screen; said magic lantern apparatus being adapted to project onto the screen, characters on the lantern slide directly in front of the lantern apparatus; the lantern slides being so arranged about the frame that the slide being projected upon the screen is related in subject matter to the record being played by the talking machine, means to turn the shaft predetermined parts of a revolution to present the proper slide in operating position before the lantern apparatus, actuated by the respective lugs in their travel to and from turntable position of the talking machine, a cam rotatably mounted on the frame, a pivotally mounted lever resting against the drum frame and shiftable by the cam, whereby upon movement of the cam in one direction, the drum will be moved along the drum shaft from rest position, and upon reverse movement of the cam, the drum will be moved to its initial rest position along the drum shaft, an electric motor, means to transmit motion from the motor shaft to the cam shaft including a clutch and a governor means adapted to operate said clutch, a coil spring positioned about a shaft whereby upon rotation of the cam shaft said coil spring is stressed, and upon disengagement of the clutch caused by action of the governor when the motor speed falls below a predetermined number of revolutions per unit of time, said coil spring will restore the cam shaft to initial rest position and an electric switch fixed on the frame; said switch including an operating arm adapted to co-operate with said talking machine component,

whereby upon movement of said component at the commencement of operation of the talking machine from initial rest position, said switch is operated to assume closed condition, and to assume open condition upon return of said talking machine component to initial rest position upon the completion of the playing of a record by the talking machine; said switch controlling the circuits of either or both said motor and the light source of the lantern apparatus.

6. An apparatus as defined in claim 5, including means adapted to retard the return movement of the cam shaft to initial rest position.

7. An apparatus as defined in claim 5, including a governor means adapted to retard the return movement of the cam shaft to initial rest position.

AL SEMELS.
